Primary Examiner — Kevin K Rudzinski*Assistant Examiner* — Paul D Bohannon(74) Attorney, Agent, or Firm — Banner & Witcoff, Ltd.(57) CLAIM

The ornamental design for a lounger, as shown and described.

DESCRIPTION

FIG. 1 is a top, front, left perspective view of a lounger showing my new design;

FIG. 2 is a front elevation view thereof;

FIG. 3 is a rear elevation view thereof;

FIG. 4 is a right elevation view thereof;

FIG. 5 is a left elevation view thereof; and,

FIG. 6 is a top plan view thereof.

The broken lines depicting the remainder of the lounger show features that form no part of the claimed design.

1 Claim, 6 Drawing Sheets(56)
